US00D773818S

(12) **United States Design Patent** (10) **Patent No.:** **US D773,818 S**
(45) **Date of Patent:** **** Dec. 13, 2016**

(54) **BACKING FOR TOOL POUCH**(71) Applicant: **L.F. Centennial Ltd.**, Road Town,
Tortola (VG)4,932,576 A 6/1990 Ashley
4,961,522 A 10/1990 Weber
4,962,873 A 10/1990 Schattel

(Continued)

(72) Inventor: **Terrence P. Kinskey**, Alpharetta, GA
(US)

FOREIGN PATENT DOCUMENTS

CA 2755685 4/2013
CA 2800605 7/2014(73) Assignee: **L.F. Centennial Ltd.**, Tortola (VG)

Primary Examiner — Holly Baynam

(**) Term: **14 Years**(74) Attorney, Agent, or Firm — Duane Morris LLP; J.
Rodman Steele, Jr.; Gregory M. Lefkowitz(21) Appl. No.: **29/518,307**(57) **CLAIM**(22) Filed: **Feb. 23, 2015**The ornamental design for a backing for tool pouch, as
shown and described.(51) LOC (10) Cl. **03-01****DESCRIPTION**

(52) U.S. Cl.

USPC ..... **D3/318**FIG. 1 is a front, perspective view in accordance with a new
backing for tool pouch design;(58) **Field of Classification Search**

FIG. 2 is a front view of the design of FIG. 1;

USPC D3/321, 318

FIG. 3 is a left side view of the design of FIG. 1;

CPC B65D 85/28; A65C 5/14; A65C 13/26

FIG. 4 is a right side view of the design of FIG. 1;

See application file for complete search history.

FIG. 5 is a top view of the design of FIG. 1;

(56) **References Cited**

FIG. 6 is a bottom view of the design of FIG. 1;

U.S. PATENT DOCUMENTS

FIG. 7 is a front, perspective view of an embodiment of the
design of FIG. 1 with a slightly taller padded portion;

D254,759 S 4/1980 Rodstein

FIG. 8 is a front view of the design of FIG. 7;

4,356,854 A 11/1982 McGee

FIG. 9 is a left side view of the design of FIG. 7;

4,390,116 A 6/1983 Fehr

FIG. 10 is a right side view of the design of FIG. 7;

4,408,706 A 10/1983 Hurley

FIG. 11 is a top view of the design of FIG. 7; and,

4,496,088 A 1/1985 Tuthill

FIG. 12 is a bottom view of the design of FIG. 7.

4,747,527 A 5/1988 Trumpower

The broken lines are included for purposes of illustrating
environment and form no part of the claimed design. The
design is not visible in the back view.

4,782,535 A 11/1988 Yewer, Jr. et al.

1 Claim, 10 Drawing Sheets

4,815,640 A 3/1989 Johnson

D302,489 S 8/1989 Stone et al.

4,917,281 A 4/1990 Ostermiller

4,923,105 A 5/1990 Snyder
